Inventor:

Joseph Humphrey

United States Patent Office.

JOSIAH HUMPHERY, OF WASHINGTON CITY, DISTRICT OF COLUMBIA.

Letters Patent No. 77,380, dated April 28, 1868.

IMPROVED SAD-IRON HOLDER.

The Schedule referred to in these Letters Patent and making part of the same.

Be it known that I, JOSIAH HUMPHERY, of the city of Washington, District of Columbia, have invented a new and improved Iron-Holder, for the purpose of lifting and handling flat-irons and other hot irons in and about stoves, ranges, furnaces, forges, &c.; and I do hereby declare that the following is a full, clear, and exact description of the construction and operation of the same, reference being had to the annexed drawings, making a part of this specification, in which—

Figure 1 is a perspective view, and

Figure 2 a transverse section.

A and A are pieces of tin, zinc, or other equivalent material, punctured so as to render their lower surface rough, like a grater or rasp, and bent in the shape indicated by the drawing. B is a straight piece of the same material, the three pieces being lined or backed with pasteboard, or some other equivalent material, which shall be a non-conductor of heat. C is a piece of ticking, or other cheap cloth, which I render partially fire-proof by washing in a solution of borax in soft water, and D is the outer covering, of leather, cloth, or other cheap and equivalent material.

The corresponding parts are represented in fig. 2 by A', B', C', and D'.

In constructing my invention, I rivet the three pieces A, A, and B to the stay-piece C, and in the relative positions indicated in the drawing, and the outer covering is then stitched on over the rivet-heads, and completes the iron-holder.

The nature of my invention consists in the combination of the three pieces A, A, and B, so that the two former shall overlap and work upon the latter, in opening and shutting the holder, in such a manner as to adjust it to the iron to be handled, while the rough inner surfaces of A and A prevent the holder from slipping. By reason of the tin or zinc A, A, and B, and of their lining, of a material which is a non-conductor of heat, the hand is prevented from becoming heated in the handling of hot irons.

What I claim as my invention, and desire to secure by Letters Patent, is—

The combination of the three pieces A B A, lined with pasteboard, or some other non-conductor of heat, punctured and made rough on their under surface, and riveted to a covering, of cloth or other cheap material, for the purpose of holding and handling flat-irons, tailors' irons, and for use about stoves, ranges, furnaces, forges, &c., the whole being constructed substantially in the manner and for the purposes described.

JOSIAH HUMPHERY.
